UNITED STATES PATENT OFFICE

LELAND K. BUTLER, OF MANCHESTER, NEW HAMPSHIRE, ASSIGNOR, BY MESNE ASSIGNMENTS, TO EXCEL TAPEING MACHINE CO., OF LYNN, MASSACHUSETTS, A CORPORATION OF MASSACHUSETTS

TAPE-APPLYING APPARATUS

Application filed January 10, 1929. Serial No. 331,550.

This invention relates to a machine for applying reinforcing tape to sheets of material such as the uppers of shoes and in some respects comprises an improvement upon the apparatus disclosed in the copending application of Jerome P. Byron No. 216,702, filed August 31, 1927 and my copending application, Serial No. 267,714, filed April 5, 1928. The above identified copending applications in general disclose mechanism particularly adapted to apply tape coated with permanently plastic adhesive and to permit such operation continuously to be effected by the movement of the tape and the sheet between a pair of rolls which are yieldably urged toward each other.

The present invention affords mechanism for cutting the tape as a portion of the same is applied to each sheet article, this mechanism being interconnected with the control means which starts and stops the feed or press rolls of the machine so that the cutting operation may automatically take place each time that the machine is stopped. Provision of means of this character facilitates production since necessity for hand cutting of the tape between successive sheet articles is avoided, and furthermore the waste of tape between successive sheet articles is also avoided. In order to permit the cutting of the tape in the most desirable manner special means are afforded to operate the cutter substantially instantaneously so that the cutting operation may take place while the tape is still moving; thus a small end portion of the severed tape section may continue in movement and may pass between the rolls and be applied to the sheet material just as the machine is being stopped. In other words, the inertia of the feed rolls and parts connected thereto permits their continued movement after the control mechanism has been operated sufficiently to effect the cutting of the tape at a point slightly before the bite of the rolls so that this small length of tape may continue along its path and be pressed into engagement with the edge of the sheet article that is leaving the rolls. Means are associated with the cutting mechanism to guide the ribbon into position between the rolls,

and to hold the severed end thereof in such a manner that it may be readily advanced into frictional engagement with the juxtaposed portions of the rolls so that successive sheet articles may have tape applied thereto and the tape may be severed between the same without substantial loss of time. In other words successive articles may be acted upon by the machine substantially as fast as they may be fed to the same and the control mechanism be operated in synchronism with the feeding operation. 55

A further aspect of the invention relates to the arrangement of the tape roll and related parts in such a manner that overfeeding of the tape is avoided. Tape of the character which is preferably used with the present machine is provided in rolls wherein concentric turns are adhesively secured to each other by a permanently plastic agglutinant. 60 As a result some of the agglutinant tends to stick to the back or uncoated surface of the tape. While the amount of adhesive thus occurring upon the back of the tape may be negligible in so far as a small section of the 65 tape is concerned, the movement of a long length of the same over the feed roll tends to deposit considerable agglutinant thereon so that the roll is rendered quite sticky and tends to cause the tape to have a very firm 70 frictional engagement therewith. As described in my prior copending application it is often desirable to run the juxtaposed feed rolls at slightly different peripheral speeds in order to effect a more firm application of 75 the tape to the shoe upper. For example, when the tape is quite yieldable and elastic I have found it advantageous to run the lower roll that engages the tape at a somewhat greater peripheral speed than the upper roll. When the lower roll becomes quite 80 sticky such a difference in speeds tends to result in the over-feeding of the tape. Accordingly the present invention affords means to compensate for this effect and to 85 permit the uniform continuous feeding of the tape under a wide variety of conditions. For this purpose I provide yieldable means arranged to take up the slack in the tape and to regulate the portion of the same which is 90 95 100

in effective engagement with the feed roll, thus automatically ensuring a constant supply of tape to the bite of the rolls. Such means also is adapted to cooperate with the bite of the rolls in holding the tape sufficiently taut readily to be acted upon by the cutter.

A machine which exemplifies the invention is illustrated in the accompanying drawings, in which:

10 Fig. 1 is a front elevational view of the improved tape applying machine;

Fig. 2 is a side elevation of the same;

Fig. 3 is a top view of a portion of the tape cutter guide and holding means;

15 Fig. 4 is an elevation of the press rolls, cutting mechanism, etc.;

Fig. 5 is a view similar to Fig. 4, but showing the parts in their cutting position;

Fig. 6 is an elevation of the cutter;

20 Fig. 7 is a top view of a ribbon guide for use when heel seams are being reinforced; and

Fig. 8 is a section on line 8—8 of Fig. 7.

A machine of the type exemplified in the accompanying drawings preferably comprises a frame designated in general by the numeral 1 which may be mounted upon any suitable table or support 2. One end of the frame preferably supports a train of gears that are driven by a belt plate 3 passing over a pulley 4 that is provided with a weighted rim and which not only comprises a flywheel but also forms a hand wheel to permit accurate manual movement of the parts when necessary. Mounted above frame 1 is a transverse shaft 7 which is rotated by a gear of the train previously referred to. The shaft is carried upon an upper roll support 12 which is pivotally connected to the frame by a pintle 13 adjoining the gear train. The overhanging end of shaft 7 carries a roll 10 for pressing the sheet material against the adhesive tape. The weight of support 12 as well as any suitable spring, not shown, may serve to press roll 10 downwardly toward the lower tape applying roll 20, which is mounted upon the shaft 11 that extends through the frame 1 and is driven by the gear train at its opposite end. A depending box-like projection 15 of support 12 may interfit with the upstanding projection 16 upon frame 1 to serve as a guide for the support. It is to be understood that the loose meshing of the gears in the gear train permits the support 12 to have a limited swinging movement in relation to the frame 1 so that the rolls 10 and 20 may be slightly separated to allow the interposition of the sheet material and tape therebetween, as fully described and explained in the above-identified applications.

A bracket 30 extends outwardly from frame 1 and supports a suitable axle 31 upon which a tape roll 32 may be located. Preferably this roll may be formed of tape

that is coated with a permanently plastic adhesive which may be pressed into firm engagement with a sheet at ordinary room temperature. Roll 32 preferably is surrounded by a suitable guard 35, a portion of which may be removable to permit replacement of the tape roll. Another portion of this guard is fixed to bracket 30 and preferably carries a roller 36 about which the tape run may be trained, and which is preferably located in substantially the same horizontal plane as the axis of the lower feed roll 20 (Fig. 2), and the tape run extends therefrom about the lower portion of that roll so that it has a firm frictional engagement with a considerable peripheral portion of the same.

Mounted on a bracket 40 secured to the end of frame 1 is a pivot element 41 about which an arm 42 is adapted to swing. This arm carries a pin or roller 44 that has its axis parallel to the axis of roll 20. One end of a spring 46 is secured to an intermediate portion of the arm 42 and has its opposite end connected to a threaded pin 48 that is 96 adjustably secured to the lower end of bracket 40 by a hand nut 49 (Fig. 2), so that adjustment of the hand nut varies the tension of the spring 46. The tape run extends from the lower portion of roll 20 to the element 44 as shown and from the latter is directed to the guide means adjoining the bite of the rolls. While such guide means may be of the general character shown in my above-identified copending application 100 it preferably is associated with the improved cutter described below.

The mechanism which operates the cutter comprises an arm 60 having its intermediate portion pivotally mounted upon shaft 11 105 between the roll 20 and the end of frame 1 (Figs. 4 and 5). The end of this arm adjoining the front of the machine is connected to the upper extremity of a control rod 61, the lower end of which is connected 110 to the rear of a control pedal 62. The rear end of arm 60 carries a dog 65 pivotally mounted thereon. A spring 67 secured to the arm 60 engages a pin 67a upon the lower end of the dog yieldably to hold the same in 115 engagement with stop 66. A fixed bracket 70 is mounted between arm 60 and the roll 20 and carries outstanding lugs 71 which have aligned openings through which knife holder 72 may slide, the latter being held 120 in a normally retracted position by a spring 77. The end of the knife carrier is provided with a striker element 73 which may conveniently comprise the head of a screw held 125 in adjusted relation to the carrier by the nut 74. Striker 73 is so positioned in relation to the upper end of dog 65 that it is engaged by the same when the dog moves upwardly in response to the downward movement of the control rod 61, Fig. 5 showing the parts 130

just as the cutter is being actuated. Figs. 3 and 6 illustrate the preferred form of knife 75 and carrier arrangement, the former being provided with a toothed or serrated edge 76 and having one projection 64 engaged in the slotted end of the carrier 72, as well as another projection juxtaposed to the rim of roll 20 to act as a guide. A stop 150 on the carrier determines the retracted position of the knife and prevents its engagement with the periphery of roll 20. The bracket 70 is provided with lugs 78 that support the projecting edge of the knife, the lower lug 78 normally being positioned to prevent accidental engagement of the tape and cutting edge of the knife when the latter is in its retracted position.

The outer end of arm 60 carries a transverse pin or tape engaging element 80 that is adapted to receive the tape run as it leaves the pin 44 and to hold the same out of engagement with the front portion of the roll 20. A pin 82 is mounted upon the arm 60 adjoining pin 80. A catch 84 is pivotally mounted upon pin 82 having its toothed edge pressed yieldably toward pin 80 by a spring 85 that engages an outstanding portion of the arm 60 so that the tape is normally gripped between its serrated edge and the pin 80, the edge being suitably beveled to permit the movement of the tape toward the bite of the rolls while catching in the surface of the same to prevent its backward movement. A sheet metal guide element 90 also is preferably pivotally mounted upon the pin 82 and is curved upwardly so that its inner end is juxtaposed to the bite of the rolls when the arm 60 is in its normal operative position. This inner end of the member 90 has a transverse slot 91 of suitable dimensions to receive and guide the tape as it passes to the rolls and is pressed thereby into adhesive engagement with a sheet article A. Preferably a suitable tongue 92 may be stuck out of member 90 and may serve to hold the tape up in a position close to the same, thus retaining the severed end of the tape in place and cooperating with the catch 84 in preventing the backward movement of the same as well as preventing the formation of a slack portion of the tape below the guide 90.

A spring 104 normally holds the nut 105 upon the upper end of rod 61 in engagement with the outstanding portion of member 60. Thus, the end of the rod is yieldably held in engagement with the swinging arm, while its lower end is connected to the rear or heel portion of the pedal 62, the intermediate part of which is pivotally mounted upon suitable support 110. A link 100 is pivotally connected to the front or toe portion of pedal 62, and its upper end is connected to the swinging crank member 112. This member has a depending arm 114 that is

adapted to press the clutch elements 116 and 117 into engagement with each other in order to impart motion to belt 3 and the machine. Another extension of crank 112 is adapted to engage a groove in the pulley 116 in order to comprise a brake, thus member 112 may be swung from a position wherein it holds the clutch elements in engagement with each other to permit the machine to be driven through belt 3 when the pulley 117 is rotated to a position wherein the clutch is released and a brake is applied to the pulley 116. The position of the control member 112 depends upon the position of pedal 62, the front portion of which when pressed downwardly, will cause the engagement of the clutch and operation of the machine, while the movement of the pedal in the opposite direction, i. e., to a position wherein the heel portion thereof is depressed, will cause the link 61 to move the arm 60 downwardly as indicated in Fig. 5, thus swinging the dog 65 up to a position where it engages striker element 73, projecting the knife 75 to a cutting position and severing the ribbon; continued downward movement of arm 60 causing the dog to pass by the corner of striker 73 and permitting the knife and knife carrier again to be retracted under the influence of spring 77. In other words, the knife is tripped almost instantaneously as the link 61 approaches the end of its downward movement. At the instant of cutting, the tape is gripped between the juxtaposed rolls, and the guide 90 and member 84 cooperate with the rolls in holding the tape in such a position that it is readily severed by the knife edge. Due to the practically instantaneous action of the knife, the tape may be severed while the machine is still in motion, and the end of the severed piece may pass to the bite of the rolls so that it is also pressed into engagement with the sheet material.

During the downward movement of arm 60 and pin 80, the member 42 is effective in taking up the resultant slack in the ribbon and in preventing the same from folding back upon itself or sticking to adjoining portions of the machine. Furthermore, the member 42 is effective in maintaining substantially uniform feeding conditions so that the length of ribbon that is engaged with the peripheral portion of roll 20 may be automatically regulated to insure constant feeding of the ribbon at the desired speed. Thus, even although roll 20 may be driven at a somewhat greater peripheral speed than roll 10 in order to assure satisfactory laying of a more or less elastic tape, any tendency of the roll to overfeed the tape is automatically avoided, even after considerable agglutinant may be deposited upon the surface of this roll. It is evident that a machine of this character may be utilized to apply adhesive tape such as reinforcing tape, to sheet arti-

cles, such as the uppers of shoes, and that as the rear edges of successive uppers near the bite of the press rolls the pedal 62 may be operated to release the clutch and to stop the movement of the rolls while automatically causing the knife to be tripped so that the tape is severed. Due to the momentum of the parts of the machine, even when the brake is applied, there may be sufficient continued movement of the rolls to permit the end of the severed tape section to be pressed into engagement with the sheet article A, and the latter to pass out from between the rolls. The starting of the machine will cause the member 90, with the projecting severed end of the tape run, to be lifted into a position where it may be engaged by the rolls when the initial edge of the succeeding sheet article is fed therebetween. The spring 104 permits the ribbon to be yieldably urged toward a position wherein it may pass between the rolls; thus undue strain upon the ribbon is avoided. A collar 125 is adjustably clamped to rod 61 and supports the lower end of spring 104 so that the compression of the latter may be varied, if desired.

During these successive operations of starting and stopping the machine, as well as all other times, the member 42 is effective in permitting uniform feeding of the tape and in avoiding the occurrence of unnecessary slack in the same or folding thereof adjoining roll 20. It is thus evident that a machine of this character permits the exceedingly rapid and convenient application of the separate sections of adhesive tape to separate sheet articles.

Figs 7 and 8 illustrate an optional form of ribbon guide 190, which may be substituted for the guide 90 described above, being particularly suitable for use when heel seams are to be reinforced by adhesive tape. Guide 190 has an intermediate portion provided with a central groove 193 designed to engage the seam and to guide the same accurately between the feed rolls. This type of ribbon guide may be provided with a tongue 192 welded or otherwise secured thereto, and functioning similarly to the tongue 92 described above. It is thus evident that a machine of this character may not only be generally used for the application of adhesively coated reinforcing tape to sheet material, but also may be arranged for specialized purposes, such as the reinforcing of heel seams.

I claim:

1. A machine of the class described comprising a pair of juxtaposed rolls adapted to receive sheet material therebetween, a roll of adhesively coated ribbon adjoining one of the aforesaid rolls and positioned to supply a run of the ribbon in frictional engagement with a peripheral portion of the same, and means disposed to receive a portion of the ribbon run between said peripheral portion

and the juxtaposed portions of the rolls, said means being adapted automatically to take up the slack in the ribbon run and to prevent overfeeding of the same.

2. A machine of the class described comprising a pair of juxtaposed rolls adapted to receive sheet material therebetween, a roll of adhesively coated ribbon adjoining one of the aforesaid rolls and positioned to supply a run of the ribbon in frictional engagement with a peripheral portion of the same, and means disposed to receive a portion of the ribbon run between said peripheral portion and the juxtaposed portions of the rolls, said means being arranged automatically to vary the extent of the ribbon in engagement with the peripheral portion of the roll to maintain a substantially constant feeding effect upon the same.

3. A machine of the class described comprising a pair of juxtaposed rolls adapted to feed sheet material therebetween, a roll of adhesively coated ribbon adjoining one of the aforesaid rolls and positioned to supply a run of the ribbon in frictional engagement with a peripheral portion of the same, and means disposed to receive a portion of the ribbon run between said peripheral portion and the juxtaposed portions of the rolls, said means comprising a ribbon engaging element yieldably urged away from the roll to keep the roll from overfeeding.

4. A machine of the class described comprising a pair of juxtaposed rolls adapted to receive sheet material therebetween, a roll of adhesively coated ribbon adjoining one of the aforesaid rolls and positioned to supply a run of the ribbon in frictional engagement with a peripheral portion of the same, and means disposed to receive a portion of the ribbon run between said peripheral portion and the juxtaposed portions of the rolls, said means being adapted automatically to take up the slack in the ribbon run and to prevent overfeeding of the same, respectively, and means between said first-named means and the juxtaposed portions of the rolls to keep the ribbon from being drawn back by said first-named means.

5. A machine of the class described comprising a pair of juxtaposed rolls arranged to receive sheet material therebetween, a roll of adhesively coated ribbon positioned to supply a ribbon run in frictional engagement with a peripheral portion of one of said rolls, guide means adapted to receive the ribbon that has left said peripheral portion and direct the same to the bite of the rolls, a cutter adapted to cast tension on and cut through the ribbon between said peripheral portion and the guide means, control linkage movable to project the cutter into cutting position, means engaging the ribbon run to move the same into the path of the advancing cutter edge, said means being operable in synchronism with the control means, and a yield-

ably mounted member to take up the slack in the ribbon run advancing to said means.

6. A machine of the class described comprising a pair of juxtaposed rolls adapted to receive sheet material therebetween, a roll of adhesively coated ribbon adjoining one of the aforesaid rolls and positioned to supply a run of the ribbon in frictional engagement with a peripheral portion of the same, and means disposed to receive a portion of the ribbon run between said peripheral portion and the juxtaposed portions of the rolls, said means being adapted automatically to take up the slack in the ribbon run and to prevent overfeeding of the same, and ribbon guiding means arranged to keep the run out of engagement with said feed roll between said first-named means and the bite of the rolls.

7. A machine of the class described comprising a pair of juxtaposed rolls adapted to receive sheet material therebetween, a roll of adhesively coated ribbon adjoining one of the aforesaid rolls and positioned to supply a run of the ribbon in frictional engagement with a peripheral portion of the same, and means disposed to receive a portion of the ribbon run between said peripheral portion and the juxtaposed portions of the rolls, said means comprising a ribbon engaging element yieldably urged away from the roll to keep the roll from overfeeding, and ribbon guiding means arranged to keep the run out of engagement with said feed roll between said element and the bite of the juxtaposed rolls.

8. A machine of the class described comprising a pair of juxtaposed rolls adapted to receive sheet material therebetween, a roll of adhesively coated ribbon positioned to supply a run of the ribbon in frictional engagement with a peripheral portion of the same, and means disposed to receive a portion of the ribbon between said peripheral portion and the juxtaposed portions of the rolls, said means being adapted automatically to take up the slack in the ribbon run and to prevent overfeeding of the same, and a cutter actuatable to sever the run between said means and the bite of the juxtaposed rolls.

9. A machine of the class described comprising a pair of juxtaposed feed rolls, mechanism to drive the same at substantially the same peripheral speed whereby sheet material may be fed between the same, control means movable in opposite directions to initiate and stop operation of the driving mechanism, and a cutter adjoining the bite of the rolls automatically operable when the control means receives one of said movements.

10. A machine of the class described comprising a pair of juxtaposed feed rolls, mechanism to drive the same at substantially the same peripheral speed whereby sheet material may be fed between the same, control means movable in opposite directions to initiate and stop operation of the driving

mechanism, and a cutter adjoining the bite of the rolls and connected to the control means to be automatically operable in response to the stopping of said feed rolls.

11. A machine of the class described comprising a pair of juxtaposed feed rolls, means supplying adhesively coated tape to the bite of the feed rolls, mechanism to drive the same at substantially the same peripheral speed whereby sheet material may be fed between the same, control means, movable in opposite directions to initiate and stop operation of the driving mechanism, and a cutter adjoining the bite of the rolls automatically operable in response to the control means to cast tension upon and cut through a run of the tape, one end of which is being gripped by the juxtaposed rolls and the other end of which is held by adhesive engagement with the tape roll.

12. A machine of the class described comprising a pair of juxtaposed feed rolls, mechanism to drive the same at substantially the same peripheral speed whereby sheet material may be fed between the same, control means movable in opposite directions to initiate and stop operation of the driving mechanism, and a cutter adjoining the bite of the rolls automatically, and trip mechanism associated with the control means and cutter instantaneously to operate the cutter when the control means is moved to stop the driving mechanism.

13. A machine of the class described comprising a pair of juxtaposed feed rolls, mechanism to drive the same at substantially the same peripheral speed whereby sheet material may be fed through the same, control means movable in opposite directions to initiate and stop operation of the driving mechanism, and a cutter adjoining the juxtaposed portion of the rolls automatically operable when the control means receives one of said movements, and means to prevent backward movement of the tape after severing.

14. A machine of the class described comprising a pair of juxtaposed feed rolls, mechanism to drive the same at substantially the same peripheral speed whereby sheet material may be fed through the same, control means movable in opposite directions to initiate and stop operation of the driving mechanism, and a cutter adjoining the juxtaposed portion of the rolls automatically operable when the control means receives one of said movements, and a tape guide normally positioned adjoining the bite of the rolls, said guide being retractable to cooperate with the rolls and hold the tape as it engages the cutter.

15. A machine of the class described comprising a pair of juxtaposed feed rolls, mechanism to drive the same at substantially the same peripheral speed whereby sheet material may be fed through the same, control means movable in opposite directions to initiate and

stop operation of the driving mechanism, and a cutter adjoining the juxtaposed portion of the rolls automatically operable when the control means receives one of said movements, and a tape guide normally positioned adjoining the bite of the rolls, said guide being retractable to cooperate with the rolls to hold the tape as it engages the cutter, and means upon the guide to prevent backward movement of the severed tape.

16. A machine of the class described comprising a pair of juxtaposed rolls arranged to receive sheet material therebetween, a roll of adhesively coated ribbon positioned to supply a ribbon run in frictional engagement with a peripheral portion of one of said rolls, guide means adapted to receive the ribbon that has left said peripheral portion and direct the same to the bite of the rolls, a cutter adapted to cast tension on and cut through the ribbon between the bite of the rolls and the guide means, and control linkage movable to project the cutter into cutting position.

17. A machine of the class described comprising a pair of juxtaposed rolls arranged to receive sheet material therebetween, a roll of adhesively coated ribbon positioned to supply a ribbon run in frictional engagement with a peripheral portion of one of said rolls, guide means adapted to receive the ribbon that has left said peripheral portion and direct the same to the bite of the rolls, a cutter adapted to cast tension on and cut through the ribbon between said peripheral portion and the bite of the rolls, control linkage movable to project the cutter into cutting position, and trip mechanism adapted to effect the substantially instantaneous action of the cutter during the movement of the control linkage.

18. A machine of the class described comprising a pair of juxtaposed rolls arranged to receive sheet material therebetween, a roll of adhesively coated ribbon positioned to supply a ribbon run in frictional engagement with a peripheral portion of one of said rolls, guide means adapted to receive the ribbon that has left said peripheral portion and direct the same to the bite of the rolls, a cutter adapted to cast tension on and cut through the ribbon between said peripheral portion and the bite of the rolls, control linkage movable to project the cutter into cutting position, and a guard adapted to keep the ribbon from engaging the cutter when the latter is in its retracted position.

19. A machine of the class described comprising a pair of juxtaposed rolls arranged to receive sheet material therebetween, a roll of adhesively coated ribbon positioned to supply a ribbon run in frictional engagement with a peripheral portion of one of said rolls, guide means adapted to receive the ribbon that has left said peripheral portion and di-

rect the same to the bite of the rolls, a cutter adapted to cast tension on and cut through the ribbon between said peripheral portion and the bite of the rolls, and control linkage movable to project the cutter into cutting position, said cutter being mounted upon a sliding carrier, said carrier being yieldably urged toward retracted position, a striker on the carrier, a swinging element mounted on a portion of the control linkage and adapted to engage and slide the carrier during a fraction of the movement of said linkage.

20. A machine of the class described comprising a pair of juxtaposed rolls arranged to receive sheet material therebetween, a roll of adhesively coated ribbon positioned to supply a ribbon run in frictional engagement with a peripheral portion of one of said rolls, guide means adapted to receive the ribbon that has left said peripheral portion and direct the same to the bite of the rolls, a cutter adapted to cast tension on and cut through the ribbon between said peripheral portion and the bite of the rolls, control linkage movable to project the cutter into cutting position, a ribbon receiving element between said peripheral portion of the roll and the guide means, said element being movable in response to the actuation of the control means to draw the ribbon taut over the cutter edge.

21. A machine of the class described comprising a pair of juxtaposed rolls arranged to receive sheet material therebetween, a roll of adhesively coated ribbon positioned to supply a ribbon run in frictional engagement with a peripheral portion of one of said rolls, guide means adapted to receive the ribbon that has left said peripheral portion and direct the same to the bite of the rolls, said means being pivotally mounted on the axle of one of the rolls, a cutter adapted to cast tension on and cut through the ribbon between the bite of the rolls and the guide means, and control linkage movable to project the cutter into cutting position, and to swing the guide means to a position wherein it will hold the ribbon in a position to be severed by the cutter.

Signed by me at Boston, Massachusetts, this 3rd day of January, 1929.

LELAND K. BUTLER.
